CONNECTION FOR ENDLESS CHAIN MECHANISM

Floyd Martin Blanchard, London, England

Application May 15, 1937, Serial No. 142,901
In Great Britain October 13, 1936

13 Claims. (Cl. 37—191)

This invention relates to bucket dredges and also to similar endless chain mechanisms, such as bucket or step or link conveyors, caterpillar tractor bands and the like. For convenience, in the following description and claims, reference will be made to dredge bucket chains, but it is to be understood that this term is intended to include other endless chain mechanisms, and that the term "dredge bucket", which will also be employed, is intended to cover also the equivalent elements of said similar mechanisms.

The front eyes of a dredge bucket are subject during service to wear and elongation. Wear is caused by a pin, not provided with a locking device, moving loosely about in the bucket eye. This wear is not confined to the bucket eye with consequent enlargement, but also causes a reduction in the diameter of the pin on one side only, towards the front of the bucket. This reduction in area causes a proportionate reduction of strength, and present-day practice is to make bucket pins of excessive diameter to offset this. Manufacturing methods demand large tolerances in machining the bucket eyes as well as in turning the diameter of the bucket pins. This is done in order to ensure an easy fit in assembly of pin and bucket. Consequently the bearing of the front eye of the bucket on the pin is never as it should be, even when new. During service, the front eyes of buckets tend to become elongated on the axis parallel to the base of the bucket. This elongation is caused by application of excessive overloads to the bucket band in order to overcome difficult and unavoidable digging conditions. The accumulation of wear and elongation causes an excessive amount of clearance between pin and bucket eye, which in turn permits undesired movement and consequent increased wear.

It is known to provide, in one of the forward eye stocks of each bucket, a recess which is adapted to accommodate an L-head integral with the bucket pin, both the recess and the L-head having parallel lateral surfaces. When the pin is first inserted this head is a driving fit in the recess, but under the twisting forces exerted by friction on the pin during the turning of the bucket about the tumblers, the head very soon slackens and allows both lateral and axial movement of the pin in the forward bucket eyes. This continued movement eventually results in excessive wear of both pin and bucket eye which is disadvantageous, because normally no provision is made for dealing with such wear, as by the provision of renewable bushes, in the forward eyes.

It has therefore been recognized that some means is desirable for locking the pin head to prevent both lateral and turning movement of the pin relative to the forward eyes in which it is located in order to eliminate wear on the pin and also in the bucket eye.

According to one means previously proposed for achieving this purpose, the L-head of a bucket pin is provided with a tapering form and coacts with tapering walls of a recess in the bucket so that when once set up the co-operation of the surfaces holds the pin rigid and also takes up pressure arising from the pull of the adjacent bucket. In practice, such a head suffers to some extent the same disadvantages as a head having parallel sides, because the tension in the bucket generally is spasmodic and repeated reversals tend to urge the pin backwards to the rear part of the forward eye, slackening the taper head and allowing a certain slackness and movement of the pin relative to the forward eye stock, with consequent wear.

It has therefore further been proposed to employ a pin having a head of tapering form in combination with a block adapted to be located between one of the lateral surfaces of the head and a lateral surface of the recess, this block being likewise tapered, but in the opposite direction to the head, to enable it to be drawn or driven so as to lock the pin head between said block and the opposite lateral surface of the recess and thereby prevent turning movement of the pin in the forward eye. However, even this additional means is subject, though to a lesser extent, to the disadvantage that the spasmodic reversals of tension in the bucket chain may drive the tapering head out of co-operation with the locking block and eventually cause the slackness which leads to movement and wear between the pin and the forward eye stocks.

The present invention provides improved means for positively locking the L-head of a bucket pin, which head is located in a recess in one of the forward eye stocks of the bucket, against movement with respect to said forward eye. The improved means comprises the combination with the bucket pin of a locking wedge adapted to engage between the end surface of said head and the end surface of the recess, for the purpose of urging the pin into firm contact with the forward part of the bucket eye, and a lateral surface of the head into engagement with the lateral surface of the recess against which it tends to bear under the twisting force applied to the pin when the bucket and that preceding it pass round one

of the tumblers, whereby the pin is embraced by abutments serving to withstand spasmodic reversals of tension in the bucket chain and also twisting forces exerted frictionally on the pin in both directions.

Preferably, the wedge is associated with screw means enabling the application of strong force to draw it between the end surfaces of the pin head and the recess.

The invention further includes the combination, in a dredge, of a pin having an L-head, a locking wedge, and a recess in one of the forward eye stocks of a bucket, the recess housing the pin head and the wedge, with the wedge engaging between the end surface of the head and the end surface of the recess, for the purpose above set forth.

In the application of screw means to the wedge in the combination last mentioned, the wedge may have a threaded shank located in a slotted abutment adjacent the recess, with a nut engaging said shank and bearing on the abutment. Alternatively, the wedge may be internally drilled or tapped to receive a drawbolt or stud mounted in an apertured abutment adjacent the recess.

If desired, the co-operating surfaces of the wedge, the recess and the head, or alternatively a lateral surface of the head and the co-operating lateral surface of the recess, may be inclined, or provided with steps, or tongues-and-grooves, for preventing axial movement of the pin when assembled.

Three embodiments of the invention will be described, by way of example, with reference to the accompanying drawings, wherein:

Fig. 1 is a side view of the base of a dredge bucket provided with one form of locking means according to the invention;

Fig. 2 is a fragmentary half-section on the line II—II—II of Fig. 1;

Fig. 3 is a view of a variation, corresponding to the left-hand part of Fig. 1;

Fig. 4 is a similar view of another variation, and

Fig. 5 is a section on the line V—V of Fig. 4.

The base of the bucket 1 is provided, as shown in Figs. 1 and 2, with a pair of forward eye stocks 2, which are spaced apart to allow the insertion between them of the rear eye stock 3 on a preceding bucket 1a. The two buckets are connected together by a pin 4 having an L-head 5 housed in a recess 6 in one of the forward eye stocks 2, passing through the forward eyes 7 of the bucket 1 and the rear eye 8 of the bucket 1a. The end surface 9 of the pin head is inclined to the longitudinal centre line of said head, and the recess 6 has an end surface 10 presented by a rib 11, which surface is substantially perpendicular to said centre line. A wedge 12 is accommodated between these end surfaces. Further, the wedge has an integral threaded shank 13, and a slot 14 is provided in a rib 15, constituting the upper wall of the recess, to enable the location of the wedge in the end of the recess prior to the insertion of the pin head. When the latter has been inserted, a nut 16, engaging the shank 13 and bearing on the upper surface of the rib 15, is turned to draw the wedge 12 upwards between the surfaces 9 and 10. Thereby, the end of the pin 4 is firmly pressed against the forward part of the eye 7, and the upper lateral surface 17 of the head 5 is caused firmly to abut the lower surface of the rib 15. The pin head is thus locked positively and rigidly against all the forces to which it is subjected

both laterally and longitudinally of the head, and movement of the pin in the forward eye stocks is thereby prevented. Wear of the forward eye 7 is accordingly avoided, such wear as occurs being confined to the rear part of the rear eye 3, where it is provided for by means of a removable anti-friction half-bush 18, as shown. Spasmodic reversals of the tension in the bucket chain are met by the solid bearing of the end surface 9 of the pin head, through the wedge 12, on the rib 11. Further, the twisting forces on the pin, which are for the most part applied clockwise in the arrangement shown as the buckets pass round the tumblers, are borne by the bearing of the surface 17 upon the rib 15, and reversed or anticlockwise twisting forces, which are usually of lesser magnitude and not so often applied, are borne by the wedge 12 against which the inclined end surface 9 of the head is firmly locked. It is therefore unnecessary to have the lower surface 19 of the head 5 in contact with the lower surface 20 of the recess 6 and a gap may conveniently be left as shown, enabling machining of said surfaces 19 and 20 to be eliminated.

In this embodiment, the surfaces 9 and 10 and the co-operating surfaces of the wedge 12 may be mutually formed to afford axial locking of the pin, or the lateral surface 17 and the co-operating surface of the rib 15 may be formed to the same end if the space between the surfaces 19 and 20 is sufficient to allow anti-clockwise displacement of the head 5 during insertion in or removal from the recess to enable such mutually locking surfaces to clear one another. The head may thus be locked with its inner surface 34 bearing on a flat boss 35 in the recess positively to prevent endwise movement of the pin.

In the variation shown in Fig. 3, the end surface 21 of the pin head 30 is disposed perpendicularly to the centre line, and the surface 22 of the abutment rib 23 is accordingly inclined to said centre line. Further, the wedge 24, as shown, has a tapped aperture 25 adapted to receive the threaded shank of a stud 26 which is passed through a slotted hole 27 in the rib 28 constituting the upper wall of the recess 29, such hole permitting forward movement of the stud.

In this arrangement again, when the wedge 24 is drawn upwards by rotation of the stud 26, the end of the pin 4 is firmly pressed against the forward part of the eye 7. Further, the upper lateral surface 31 of the head 30 is frictionally urged by the wedge 24 against the lower surface 28 of the rib 28. Spasmodic reversals of the tension in the bucket chain are supported by the solid bearing of the end surface 21 of the pin head 30, through the wedge 24, on the rib 23. Major or clockwise twisting forces on the pin are supported by the abutment of the surface 31 of the latter against the rib 28.

In this arrangement, endwise locking of the pin against the boss 35 may be ensured by suitably forming of the surfaces 21 and 22 and the co-operating surfaces of the wedge 24.

Figs. 4 and 5 show in elevation and in section another variation, wherein the head 36 of a pin 4 is reduced in size, with consequent reduction of weight and cost of material. The arrangement includes a wedge block 37 located between the end surface 38 of the pin head 36 and an abutment surface 39 of a rib 40 of the bucket structure, which surfaces are both inclined, in opposite directions, to the longitudinal axis of 75.

the head. Further, both the surfaces 38 and 39 are also inclined in plan, and the coating surfaces of the wedge block 37 are correspondingly inclined, so that the block is substantially rhomboidal in horizontal section at or about its middle, as shown in Fig. 5. A drawbolt 41 extends completely through a drilling in the wedge block, the bolt head 42 being housed in a recess in the lower part of the block. The bolt extends upwards through a hole 43 in a rib 44, which hole is splayed downwards, as shown in Fig. 4, to enable the insertion of the associated bolt and wedge block when the pin head 36 is already located in the recess, and is also slotted to allow longitudinal movement of the bolt as the wedge is drawn up. A nut 45, which engages the bolt, bears on the upper surface of the rib 44 and serves by the interaction of the wedge block 37 and surface 38 to draw the upper lateral surface 46 of the pin head 36 into engagement with the lower abutment surface 47 of the rib 44, to lock the pin positively against turning movement in the eye 7. At the same time the pin is pressed forward against the front half of the eye 7, to prevent movement under spasmodic variations or reversals of tension in the bucket chain, any reversals which occur being supported by the solid bearing of the pin head 36 through the wedge block 37, on the rib 40. Further, the inclination in plan of the surfaces 38 and 39 cause the wedge when drawn up by the bolt 41 to press both its own inner surface 48 and the inner surface 34 of the pin head 36 against a flat boss 35 in the back of the recess, to effect positive locking together of the parts and prevent endwise movement of the pin 4.

Evidently, other constructional variations may be made, as by providing the wedge block in an embodiment similar to any of those shown with an integral shank, a stud or a drawbolt according to convenience. Further, modifications may be made as required, for example, in applying the invention to other endless chain mechanisms, such as link conveyors, tractor bands and the like above referred to.

I claim:—

1. For use in a dredge bucket having a forward eye stock with a circular eye and a recess the periphery of which is constituted by upper and lower surfaces joined by one part-cylindrical end surface and one transverse plane end surface, the combination of a bucket pin locatable in said eye, an L-head on said pin adapted to lodge in said recess, a plane end surface on said head, and a locking wedge block adapted to engage between said plane end surfaces to urge said head into firm contact with said part-cylindrical surface.

2. For use in a dredge bucket having a forward eye stock with a circular eye and a recess the periphery of which is constituted by upper and lower surfaces joined by one part-cylindrical end surface coincident with the periphery of said eye and one transverse plane end surface, the combination of a bucket pin locatable in said eye, an L-head on said pin adapted to lodge in said recess, a plane end surface on said head, a locking wedge block adapted to engage between said plane end surfaces, and screw means associated with said wedge block to draw it between said plane end surfaces to urge said pin into firm contact with said part-cylindrical surface.

3. Connection for endless dredge bucket chain comprising the combination of a forward bucket eye stock, a circular eye in the stock, a recess in the outer surface of the stock, the periphery

of said recess being constituted by upper and lower surfaces joined by one part-cylindrical end surface and one transverse plane end surface, a pin extending through the eye, an L-head on the pin lodged in said recess, a plane end surface on said head, and a transverse locking wedge block engaging between said plane end surfaces to urge the head into firm contact with said part-cylindrical surface. 5

4. Connection for endless dredge bucket chain 10 comprising the combination of a forward bucket eye stock, a circular eye in the stock, a recess in the outer surface of the stock, the periphery of said recess being constituted by upper and lower surfaces joined by one part-cylindrical end 15 surface coincident with the periphery of the eye and one transverse plane end surface, a pin extending through the eye, an L-head on the pin lodged in said recess, a plane end surface on said head, a transverse locking wedge 20 engaging between said plane end surfaces, an apertured abutment on the recessed eye stock adjacent the recess, a screw-threaded shank on the wedge block passing through said apertured abutment and a nut on the shank turnable to draw 25 the wedge block transversely between said plane end surfaces to urge the pin into firm contact with said part-cylindrical surface.

5. Connection for endless dredge bucket chain 30 comprising the combination of a forward bucket eye stock, a circular eye in the stock, a recess in the outer surface of the stock, the periphery of said recess being constituted by upper and lower surfaces joined by one part-cylindrical end 35 surface coincident with the periphery of the eye and one transverse plane end surface, a pin extending through the eye, an L-head on the pin lodged in said recess, a plane end surface on said head, a transverse locking wedge block 40 engaging between said plane end surfaces, an apertured abutment on the recessed eye stock adjacent the recess, and a drawbolt extending through said abutment and engaging the wedge block for drawing it transversely between said plane end surfaces to urge the pin into firm contact with 45 said part-cylindrical surface.

6. Connection for endless dredge bucket chain 50 comprising the combination of a forward bucket eye stock, a circular eye in the stock, a recess in the outer surface of the stock, the periphery of said recess being constituted by upper and lower surfaces joined by one part-cylindrical end 55 surface coincident with the periphery of the eye and one transverse plane end surface, a pin extending through the eye, an L-head on the pin lodged in said recess, a plane end surface on said head, a transverse locking wedge block 60 engaging between said plane end surfaces, an apertured abutment on the recessed eye stock adjacent the recess, a screw-threaded shank on the wedge block passing through said apertured abutment and a nut on the shank turnable to draw the wedge block transversely between said plane end surfaces to urge the pin into firm contact with said part-cylindrical surface, said apertured abutment being formed to permit insertion of the wedge-block in the recess prior to the insertion of the pin head. 65

7. Connection for endless dredge bucket chain 70 comprising the combination of a forward bucket eye stock, a circular eye in the stock, a recess in the outer surface of the stock, the periphery of said recess being constituted by upper and lower surfaces joined by one part-cylindrical end 75 surface coincident with the periphery of the eye

and one transverse plane end surface, a pin extending through the eye, an L-head on the pin lodged in said recess, a plane end surface on said head, a transverse locking wedge engaging between said plane end surfaces, an apertured abutment on the recessed eye stock adjacent the recess, and a drawbolt extending through said abutment and engaging the wedge block for drawing it transversely between said plane end surfaces to urge the pin into firm contact with said part-cylindrical surface, said apertured abutment being formed to permit insertion of the L-head in the recess prior to the insertion of the wedge block between the end surfaces and the drawbolt associated therewith through the apertured abutment.

8. For use in a dredge bucket having a forward eye stock with a circular eye and a recess the periphery of which is constituted by upper and lower surfaces joined by one part-cylindrical end surface and one transverse plane end surface inclined in end elevation to the longitudinal axis of said recess, the combination of a bucket pin locatable in said eye, an L-head on said pin adapted to lodge in said recess, a plane end surface on said head, and a locking wedge block adapted to engage with surface contacts between said plane end surfaces to urge said head into firm contact with said part-cylindrical surface.

9. For use in a dredge bucket having a forward eye stock with a circular eye and a recess the periphery of which is constituted by upper and lower surfaces joined by one part-cylindrical end surface and one transverse plane end surface normal in end elevation to the longitudinal axis of said recess, the combination of a bucket pin locatable in said eye, an L-head on said pin adapted to lodge in said recess, a plane end surface on said head inclined in end elevation to the longitudinal axis of said head, a locking wedge block adapted to engage with surface contacts between said plane end surfaces, and screw means associated with said wedge block to draw it between said plane end surfaces, one effective surface of the wedge block engaging the end surface on the head with surface contact, said end surface on the head being inclined in end elevation to the longitudinal axis of the head and also inclined in plan to said axis to enable the wedge block to urge said pin into firm contact with said part-cylindrical surface and into the recess for positively preventing endwise movement of the pin, and the other effective surface of the wedge block being inclined in end elevation to said axis.

10. Connection for endless dredge bucket chain comprising the combination of a forward bucket eye stock, a circular eye in the stock, a recess in the outer surface of the stock, the periphery of said recess being constituted by upper and lower surfaces joined by one part-cylindrical end surface and one transverse plane end surface inclined in end elevation to the longitudinal axis of said recess, a pin extending through the eye, an L-head on the pin lodged in said recess, a plane end surface on said head normal in end elevation to the longitudinal axis of said head, and a transverse locking wedge block engaging with surface contacts between said plane end surfaces to urge the head into firm contact with said part-cylindrical surface.

11. Connection for endless dredge bucket chain comprising the combination of a forward bucket eye stock, a circular eye in the stock, a recess in the outer surface of the stock, the periphery of said recess being constituted by upper and

lower surfaces joined by one part-cylindrical end surface coincident with the periphery of the eye and one transverse plane end surface normal in end elevation to the longitudinal axis of said recess, a pin extending through the eye, an L-head on the pin lodged in said recess, a plane end surface on said head inclined in end elevation to the longitudinal axis of said head, a transverse locking wedge engaging with surface contacts between said plane end surfaces, an apertured abutment on the recessed eye stock adjacent the recess, a screw-threaded shank on the wedge block passing through said apertured abutment and a nut on the shank turnable to draw the wedge block transversely between said plane end surfaces to urge the pin into firm contact with said part-cylindrical surface.

12. For use in a dredge bucket having a forward eye stock with a circular eye and a recess the periphery of which is constituted by upper and lower surfaces joined by one part-cylindrical end surface coincident with the periphery of said eye and one transverse plane end surface, the combination of a bucket pin locatable in said eye, an L-head on said pin adapted to lodge in said recess, a plane end surface on said head, a locking wedge block adapted to engage between said plane end surfaces, and screw means associated with said wedge block to draw it between said plane end surfaces, one effective surface of the wedge block engaging the end surface on the head with surface contact, said end surface on the head being inclined in end elevation to the longitudinal axis of the head and also inclined in plan to said axis to enable the wedge block to urge said pin into firm contact with said part-cylindrical surface and into the recess for positively preventing endwise movement of the pin, and the other effective surface of the wedge block being inclined in end elevation to said axis.

13. Connection for endless dredge bucket chain comprising the combination of a forward bucket eye stock, a circular eye in the stock, a recess in the outer surface of the stock, the periphery of said recess being constituted by upper and lower surfaces joined by one part-cylindrical end surface coincident with the periphery of the eye and one transverse plane end surface inclined in end elevation to the longitudinal axis of said recess and also inclined in plan to said axis, a pin extending through the eye, an L-head on the pin lodged in said recess, a plane end surface on said head inclined in end elevation to the longitudinal axis of said head and also inclined in plan to said axis, a transverse locking wedge block engaging between said plane end surfaces with surface contacts, an apertured abutment on the recessed eye stock adjacent the recess, and a drawbolt extending through said abutment and engaging the wedge block for drawing it transversely between said plane end surfaces to urge the head into firm contact with said part-cylindrical surface and into the recess for positively preventing endwise movement of the pin.

FLOYD MARTIN BLANCHARD.
